Primary Examiner — Sheryl Lane*Assistant Examiner* — Emily A Caven(74) *Attorney, Agent, or Firm* — PatentFile, LLC; Bradley C. Fach; Steven R. Kick(57) **CLAIM**

The ornamental design for a bird fluid feeder device, as shown and described.

DESCRIPTION

FIG. 1 is a front elevation view showing the new, original, and ornamental design of a bird fluid feeder device; FIG. 2 is a right elevation view thereof, the left side being a mirror image;

FIG. 3 is a rear elevation view thereof;

FIG. 4. is a bottom plan view thereof;

FIG. 5 is a top plan view thereof; and,

FIG. 6 is a perspective view thereof.

The broken lines are included for the purpose of illustrating portions of the bird fluid feeder device which form no part of the claimed design.

1 Claim, 6 Drawing Sheets(56)
